United States Patent Office

Des. 189,435
Patented Dec. 13, 1960

189,435

PHONOGRAPH

David C. Rockola, Chicago, Ill., assignor to Rock-Ola Manufacturing Corporation, Chicago, Ill., a corporation of Delaware

Filed Apr. 2, 1959, Ser. No. 55,323

Term of patent 3½ years

(Cl. D56—4)

Fig. 2 is a side elevational view; and

Fig. 3 is a top plan view thereof.

I claim:

The ornamental design for a phonograph, substantially as shown.
